Des. 180,076
Patented Apr. 16, 1957

180,076

RECORDER USED IN DETERMINING PROGRAM RATINGS

Robert L. Freeman, Evanston, and Elizabeth A. Kucera,
Norwood Park Township, Cook County, Ill., and Donald F. Bean, Oakland, Calif., assignors to A. C. Nielsen
Company, Chicago, Ill., a corporation of Illinois

Application October 15, 1954, Serial No. 32,684

Term of patent 14 years
(Cl. D26—14)

Fig. 1

Fig. 2.

Fig. 3.

Fig. 4.

Fig. 1 is a perspective view of a recorder used in determining program ratings, showing our new design;
Fig. 2 is an enlarged front elevational view thereof;

Fig. 3 is an end elevational view thereof; and
Fig. 4 is a top plan view thereof.

We claim:

The ornamental design for a recorder used in determining program ratings, substantially as shown.
